(57) **CLAIM**

The ornamental design for a dental membrane, as shown and described.

DESCRIPTION

FIG. 1 is a front perspective view of my dental membrane;
FIG. 2 is a front view;
FIG. 3 is a rear view;
FIG. 4 is a left side view;
FIG. 4A is an enlarged view of the encircled portion of FIG. 4;
FIG. 5 is a right side view;
FIG. 6 is a top view;
FIG. 7 is a bottom view; and,
FIG. 8 is a perspective view of the dental membrane in an installed orientation.
The dashed lines form no part of the claimed design and illustrate environment only.
